HEAT TRANSFER ELEMENT

Arthur B. Modine, St. Petersburg, Fla.

Application July 14, 1941, Serial No. 402,265

5 Claims. (Cl. 257—128)

The invention relates generally to heat transfer elements or cores, and more particularly to a novel method and means of constructing and assembling the same.

The invention has among its objects the production of a heat transfer element or core of steel and copper or other suitable materials, wherein the desirable tensile characteristics of the one metal is complemented by the desirable thermo characteristics of the other metal.

Another object of the invention is the production of such a core in which the various elements or units of the core are of such material and so shaped that a bonding material of relatively high heat conductivity may be employed to bond the various units together.

A further object of the invention is the production of such a core in which the elements or units thereof are so shaped that a surplus of molten bonding material which is very fluent and will readily flow from one point to another may be collected at certain points thereof to increase the heat transfer capacity of the device.

A further object of the invention is the production of a novel method for constructing such devices which is relatively simple and very efficient, whereby a single bonding operation is required in the construction of the device.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a perspective view of a radiator core or the like embodying the present invention;

Fig. 2 is a sectional view taken substantially on line 2—2 of Fig. 1;

Fig. 3 is a sectional view taken approximately on the line 3—3 of Fig. 1, with portions of the upper and lower headers broken away;

Fig. 4 is a perspective view of a portion of the assembly, illustrating the construction thereof;

Fig. 5 is a perspective view similar to Fig. 4 showing the assembly prior to the bonding operation;

Fig. 6 is a perspective view of a portion of the core assembly, with the upper portion broken away;

Fig. 7 is a perspective view illustrating a slightly different construction and showing one means

of applying the bonding material prior to the bonding operation;

Fig. 8 is a similar view of the same after the bonding operation;

Fig. 9 is a view similar to Fig. 7, illustrating another manner of initially securing the bonding material to the core units; and

Fig. 10 is a view of the construction illustrated in Fig. 9 after bonding.

- 10 The present invention contemplates a core structure built up of a series of elements or units which are constructed of a material having a relatively high melting point in combination with a bonding metal having a relatively lower melting point, wherein the bonding material has relatively high heat conductivity. In actual practice one combination of metals used could be that of steel and copper, the latter being used for the bonding material and the steel for the core structure. 15 The characteristics of the steel are such that it would withstand the temperatures necessary to melt the copper during the bonding operation and yet have sufficient tensile strength to meet the requirements of the device. Likewise, 20 the same metal might be employed for both the structure and the bonding material, with one or both being alloyed with other metals to achieve the desired results, the heat conductivity of the bonding material, however, being substantially 25 not less than that of the structure material. The core elements or units are preferably so shaped that a surplus of the melted copper will flow during the bonding operation and collect at certain points, where it will be most efficient in the 30 transfer of heat.

Referring to the drawings, Fig. 1 illustrates the application of the invention to a radiator core or the like, 1 designating generally a core having upper and lower headers 2 and 3, the 40 upper header 2 being provided with a fluid inlet 4 and the lower header with a corresponding outlet. The core 1 comprises a plurality of individual fin units or elements 5 which are vertically arranged or stacked in banks 6. These banks 45 are positioned adjacent one another, spacer strips 7 being interposed intermediate each pair of banks at opposite ends of the units or elements 5. The fin units or elements 5 each comprise a fin portion 11 having side walls 12 extending 50 transversely therefrom adjacent the longitudinal edges of the fin portion. The side walls 12 are provided adjacent their free longitudinal edges with opposed inwardly extending flanges 13, the latter being spaced from one another as clearly illustrated in Figs. 3, 4 and 5. The units or ele-

ments 5 are constructed from relatively thin sheet material having a relatively high melting point, such as steel, the units being vertically stacked in banks 6, as shown in Fig. 3, with the flanges 13 of each unit positioned adjacent to the fin portion 11 of the adjoining unit and bonded thereto, as shown at 14 in Fig. 3. The banks 6 are positioned adjacent one another and are connected with the spacing bars or strips 7 as shown in Fig. 6, the latter strips likewise being bonded to the adjacent banks to form passages 15 therebetween, the side walls of the passages being formed by the side walls 12 of the respective fin units or elements with the spacers 7 forming the end walls of said passage.

Secured to the top and bottom of the core are upper and lower headers 2 and 3. Any suitable header construction may be employed. In the embodiment of the invention illustrated plate 16 of approximately the same length and width as each of the fin portions 11 of the respective units 5 are positioned adjacent the flanges 13 of the bottom units to close the same. The headers are provided with internal flanges 17 secured to the cores illustrated in Figs. 2 and 3 by suitable bonding means. Thus fluid enters the inlet 4 in the upper header 2 and passes into the lower header and through the outlet therein. As the fluid travels through passages 15 the heat will be conducted through the side walls 12, fin portion 11 and flanges 13 and is absorbed by the air passing through the openings or passages 18 formed by the respective units. This construction is similar to that illustrated in my co-pending application Serial No. 383,529.

In the preferred embodiment of the invention the fin portion 11 of the respective units is provided with a series of cavities or indentations 19, the latter, in the present instance, being triangular in shape and tapering in depth from the side wall 12 to the central portion of the fin, so that the portion of greatest depth is adjacent the side walls 12. The cavities 19 provide means for collecting the molten copper bonding material, which is very fluent, adjacent the side walls 12 of the units, the preponderance of the copper being closely adjacent to the side wall and diminishing in amount toward the center of the fin portion. Thus the fin portion in its final form is of bi-metal construction in effect tapering in thickness from adjacent the side walls 12 to the center of the fin portion. Due to the high efficiency of the copper as a heat conductor, the heat transfer capacity of a core embodying the present construction is considerably increased.

The device may be assembled and bonded in the following manner, illustrated in Figs. 4 and 5 wherein Fig. 4 shows the bonded structure and Fig. 5 the condition prior to bonding: The fin units or elements 5 are vertically stacked in proper relationship to one another to form a bank 6, a strip of copper 21 of substantially the same width as the fin portions 11 being inserted intermediate the respective units. If desired the strips 21 may be spot-welded or otherwise suitably attached to its respective unit to insure proper positioning of the strip relative to the unit. The spacers 7 are then positioned intermediate the banks at the respective ends of the units and the whole placed in a hydrogen furnace. The latter is brought up to a temperature sufficient to melt the copper, which will readily flow into the cavities 19, filling the same, between the respective flanges 13 and the fin portions 11 to effectively bond the same together. During this

operation the stacks or banks of units are preferably placed under compression to prevent all of the molten copper from flowing down the sides of the units, the molten copper being very fluent, readily flowing from one point to another. The copper bonding material may be applied to the spacers 7 in any suitable manner, as for example, by copper plating before being assembled with the units. The sheet of copper 21 is of sufficient thickness to provide an excess of metal to insure the filling of the cavities 19, and during the bonding operation will flow down along the side walls 12 of the units to provide a thin coating of copper which may form a protective coating over the side walls, protecting the same from the action of fluids that may pass through the device.

Illustrated in Figs. 7 through 10 is a slightly different form of construction utilizing a slightly different method of assembly. In the construction illustrated in Fig. 7 before bonding and Fig. 8 after bonding the fin portions 31 are elevated slightly at the central portion thereof as shown at 32, whereby the fin portion slopes downwardly from the central portion to the side walls forming an inverted V-shaped fin. The flanges 33 also conform to the slope of the adjoining fin portions. The copper strip 21' is positioned adjacent its respective fin portion, the strip likewise conforming to the shape of the fin portion. When the assembled core is placed in the furnace or oven for bonding, upon melting of the copper the latter will flow outwardly toward the side walls 34 and the surplus molten copper will collect adjacent the latter, thereby forming a bi-metal fin tapering toward the central portion thereof with the heaviest portions of the fin being adjacent the side walls.

Illustrated in Figs. 9 and 10 is a similar construction illustrating a slightly different method of assembling the same, wherein Fig. 9 shows the unit prior to bonding and Fig. 10 after bonding. In this modification the fin portion 31 is provided with a thin coating 35 of copper on the upper face thereof, a thin sheet 36 of copper is positioned within the unit, the sheet resting on the flanges 33, the latter in this instance being bent outwardly away from the fin portion, as clearly illustrated in Fig. 9. As the bonding copper melts it will likewise flow toward the side walls 34, the stacks or banks of fin units being compressed to bend the flanges 33 into the position illustrated in Fig. 10. This action forms an effective seal between the units and precludes the possibility of the major portion of the molten bonding material flowing down the sides of the units and assures the flowing of the metal to the proper points. This construction may also be employed with the other forms illustrated. The finished article, as illustrated in Fig. 10, is substantially the same as that illustrated in Fig. 8.

While I have shown several different ways in which the bonding material may be initially positioned or assembled with respect to the units or elements, obviously the bonding material may be applied in any suitable manner, as for example, by plating, spraying, the use of flat sheets as illustrated, or by the use of granules. It will be apparent from the above description that I have provided a heat transfer core or unit in which the desirable characteristics of the steel structure are combined with the desirable characteristics of the copper to provide a core of great durability having a relatively high heat transfer capacity. Likewise, I have produced a novel method of assembling the same, whereby the

unit may be entirely bonded in a single operation, and have produced a novel fin construction wherein excess or surplus molten bonding material is collected at desired points to produce highly beneficial results. While I have described the core as being constructed of steel and copper, obviously the invention is not limited to the use of these two metals, but may be utilized with other combinations of metals having suitable tensile and thermo characteristics.

Having thus described my invention, it is obvious that various immaterial modifications may be made in the same without departing from the spirit of my invention; hence, I do not wish to be understood as limiting myself to the exact form, construction, arrangement and combination of parts herein shown and described, or uses mentioned.

What I claim as new and desire to secure by Letters Patent is:

1. In a radiator of the kind described, a plurality of channel-shaped units stacked one upon the other and each having leg members connected by a flat wall, said wall being adapted to form a divider and heat exchange member in the air passageways of the radiator, bonding material to join each unit to an adjacent unit to provide a bank of units, means for securing a plurality of said banks together in spaced relation to provide a fluid passage between the banks, said bonding material being of equal or greater heat conductivity than that of said units, and said flat wall of each unit having transverse depressions formed therein to direct and conduct a preponderance of bonding material toward the leg ends of the flat wall of each unit to join the legs of the adjacent unit therewith.

2. In a device of the kind described, comprising a plurality of elements arranged in banks, spacers at opposite ends of each bank separating adjacent banks to provide fluid passages therebetween, each of said elements comprising a fin member, downwardly extending side walls carried by each of said members, said side walls being formed with inwardly extending flanges flatly engageable with the fin member of the adjacent element, bonding material for joining said elements, said fin members each having a plurality of depressions in the top face thereof terminating at points beneath the adjacent faces of said inwardly extending flanges that contact the adjacent fin member, said depressions increasing in depth toward the aforesaid points to direct a preponderance of bonding material thereto.

3. In a device of the kind described comprising a plurality of elements arranged in banks to provide fluid passages therebetween, each of said elements comprising a fin member, downwardly extending side walls carried by each of said members, said side walls being formed with inwardly extending flanges engageable with the fin member of the adjacent element, bonding material for joining said flanges to said adjacent elements, and said fin members each having a plurality of troughs offset from the surface thereof for directing the bonding material in steadily increasing depth toward said side walls and beneath the flanges of the adjacent fin members to increase the total metallic thickness of the respective fin members adjacent said side walls during the bonding process.

4. A heat transfer core comprising a plurality of units joined together to form fluid and air passages, said units providing a plurality of fins extending across said air passages, bonding material for joining said units, said bonding material being of substantially equal or greater heat conductivity than the material of said units, and said fins of each unit having independent rows of transverse depressions formed therein with each depression beginning intermediate the breadth of the fin and extending in steadily increasing depth and width toward the longitudinal sides thereof to collect a preponderance of bonding material adjacent the juncture of said fins and side walls of said passages to increase the heat transfer characteristics of said device.

5. In a device of the kind described comprising a plurality of elements arranged in banks to provide fluid passages therebetween, each of said elements comprising a fin member, downwardly extending side walls carried by each of said members, said side walls being formed with inwardly extending flanges engageable with the fin member of the adjacent element, bonding material for joining said flanges to said adjacent element, and said fin members each having troughs formed in the face thereof, said troughs each beginning intermediate the sides of the fins and extending toward the edges thereof in steadily increasing size, and terminating at the edges of the fin with the troughs in close contact with each other to form a substantially continuous well portion along the edges of each fin for collecting the bonding material in a predetermined mass located with the greatest amount thereof disposed at the juncture of the fins and the side walls.

ARTHUR B. MODINE.
